COMBINED BUNK BED AND STORAGE UNIT

Michael A. Mendlin, Springfield, N.J., assignor to Bunk
Trunk Distributors, Paramus, N.J.

Filed July 6, 1971, Ser. No. 160,257

Term of patent 14 years

Int. Cl. D6—01

U.S. Cl. D6—80

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 13

FIG. 14

FIG. 15

FIG. 1 is a front elevational view of a combined bunk bed and storage unit showing my new design;

FIG. 2 is a right side elevational view thereof;

FIG. 3 is a left side elevational view thereof;

FIG. 4 is a rear elevational view thereof;

FIG. 5 is a top plan view thereof;

FIG. 6 is a bottom plan view thereof;

FIG. 7 is a perspective view of a combined bunk bed and storage unit showing a second embodiment of my new design, which differs from the first embodiment in the addition of a trundle bed;

FIG. 8 is a front elevational view of a combined bunk bed and storage unit showing a third embodiment of my new design, which differs from the first embodiment in the addition of a three-drawer storage unit;

FIG. 9 is a perspective view of a combined bunk bed and storage unit showing a fourth embodiment of my new design; which differs from the first embodiment in the replacement of the storage closet of the left column unit by a column of storage shelves, and by the addition of two storage shelves on the inside of the left column unit.

FIG. 10 is a front elevational view thereof;

FIG. 11 is a rear elevational view thereof;

FIG. 12 is a left side elevational view thereof;

FIG. 13 is a right side elevational view thereof;

FIG. 14 is a bottom plan view thereof; and

FIG. 15 is a top plan view thereof.

I claim:

The ornamental design for a combined bunk bed and storage unit, substantially as shown and described.
